UNITED STATES PATENT OFFICE.

DANIEL J. O'CONNOR, OF NEW YORK, N. Y., ASSIGNOR TO TWISTED WIRE & STEEL CO., OF NEW YORK, N. Y.

BOX-STRAPPING TOOL.

1,413,768.

Specification of Letters Patent. Patented Apr. 25, 1922.

Application filed May 21, 1921. Serial No. 471,367.

To all whom it may concern:

Be it known that I, DANIEL J. O'CONNOR, a citizen of the United States, and a resident of the city, county, and State of New York, 5 (whose post-office address is 437 Eleventh Avenue, New York city,) have invented certain new and useful Improvements in Box-Strapping Tools, of which the following is a specification.

10 My invention relates to that class of box-strapping tools in which the free ends of box-strapping or other material, are drawn together under desired tension by means of a sliding block or gripping carriage traveling along a fixed track toward a stationary gripping device, or by drawing said track and gripping device toward said block, as tension requires.

15 The object of my invention is to do away with the rack and pinion mechanism frequently used in tools of this class, and to bring about the necessary stretching of the strapping by means of a drum and cable mechanism, whereby the efficiency and simplicity of the tool are much improved and the tool itself rendered more durable and reliable.

20 One form of my invention is shown in the accompanying drawings in which:—

25 Figure 1, is a side view.

Figure 2, is a top plan.

Figure 3, is an enlarged detail of the drum.

30 Figure 4, is a cross section on line 4—4 of Figure 1.

Figure 5, is a top plan of the drum showing the cable wound thereon.

35 Same letters indicate similar parts in the different drawings.

40 A, B, are two gripping blocks, of substantially similar construction but facing in opposite directions. Both of these blocks are provided with a cam-lever a, a , pivoted to the block at b, b , and having a gripping cam

45 surface c, c , adapted to grip a free end of box-strapping when inserted thereunder against the rest d, d , forming part of the base of the block. This pressing action is constant, being caused by the coiled spring e, e , wound around the pivot of the lever and secured to the wall of the block. This feature is of well-known construction.

50 The other portion of each block is slotted as at f, f , Figure 4, to receive a slide bar, 55 preferably T-shaped, and which is prefer-

ably secured to block B, as at g , while it may slide freely through the slot in block A. This slide bar, C, is provided, preferably, with a longitudinal trough h , in which runs the cable D, one end of which is fastened to 60 the slide bar by the same fastening g which holds the latter to the block B. In this way the pull of the cable as it winds, exerts balanced force upon block and slide during the tightening operation. 65

E is a sliding carriage, firmly secured to the slide block A, as by screw j , or in other suitable manner, and slotted as at k , to permit free passage to the slide bar C, and the cable D. In the centre of this carriage is 70 mounted by shaft l , a drum F, the periphery of which is grooved to receive the cable D, the end of which is fastened thereto, as it winds up during the tightening operation of the tool. 75

G is the handle, preferably forked to infold the drum which is, preferably, narrow,—the ends of the fork being loose on the pin or shaft l , while the drum is fast to said shaft. Each side-surface of the drum F, is 80 provided with beveled ratchet teeth m, m , and each arm of the fork of the handle G, is provided with a spring-controlled dog, n, n ,—the two dogs acting in unison to engage the corresponding teeth on opposite sides of the drum, and thus cause the same to revolve evenly, the pressure on both sides being the same. 85

The drum is prevented from turning backward under tensional strain, when the dogs are drawn back by the handle G, to catch another tooth of the drum F, by a spring-controlled pin, p, p , projecting through the sidewall of the carriage E, and held under pressure by the spring r, r . 90 This spring is preferably flat while spring s, s , of the dog n, n , is coiled. 95

The operation of my improved tool will be readily understood by those skilled in the art. One end of the box-strapping is 100 placed under the gripping device A and the other end under the gripping device B, facing each other. By means of the handle G, the drum F, is turned partly round thus winding up the cable D, and drawing the 105 two gripping devices A, B, to each other,—the two strap ends thus overlapping. Step by step this process goes on till the box-strapping has been brought to the desired tension. The overlapping ends are then se- 110

cured together in the usual way by a suitable tool and the carriage E is drawn back to its initial position ready to receive another length of box-strapping.

5 I claim:—

A box-strapping tool which comprises gripping devices by which the free ends of box-strapping are held during the opera-

tion of tightening and securing the same, and a drum and cable mechanism whereby the tightening thereof is effected.

DANIEL J. O'CONNOR.
